KARL STEGMANN, OF BAUTZEN, GERMANY, ASSIGNOR TO JOHNE-WERK GRAFISCHE MASCHINEN-AKTIENGESELLSCHAFT, OF BAUTZEN, GERMANY

PILE COMPRESSING MEANS FOR PAPER CUTTING MACHINES AND THE LIKE

Application filed August 7, 1930, Serial No. 473,654, and in Germany October 30, 1929.

This invention has reference to cutting machines for paper, cardboard and the like and in particular to pressing means for the purpose of securing in position the piles of paper or cardboard which are to be submitted to the cutting operation, and it is intended to facilitate the manipulation and increase the accuracy of devices of the kind referred to. Broadly considered the invention is particularly adapted to machines of this kind with manually operated screw shafts and the like. For the purposes referred to highly expensive superior grades of modern machines with great efficiency and possessing automatic power-driven pressing means and the like have been constructed, but aside from these expensive and complicated kinds of machinery the trade, and particularly smaller kinds of printing establishments require less costly simple machines which however should possess likewise a very satisfactory comparatively high rate of efficiency. In the devices heretofore suggested for this purpose the compression of the pile was effected manually by means of a screw shaft or a screw spindle and, in order to produce the compression several revolutions of the hand wheel had to be performed, so as to require the operator, when using both hands to change the position of his hands at least four times in the grasping and the operation of the spindle, until the pile could be sufficiently compressed. Moreover in this manipulation the machine was liable to be strained too much unless the operator was skillful enough and possessed the required delicate sense of feeling to judge of the proper amount of pressure.

Now in accordance with this invention these difficulties are avoided by providing the pressure producing screw shaft with steep, and not automatically locking threads. By this means automatic rotation of the screw spindle is prevented by the aid of suitable stopping means adapted to secure the pressing spindle in its particular operating position. In a preferred construction frictionally acting arresting means may be used for this purpose.

On the accompanying drawing an embodi-

ment of the principles of the invention is shown by way of exemplification in Fig. 1 partly in elevation and partly in section—Fig. 2 is a section on line *a—a* of Fig. 1.

The pile of paper or cardboard is compressed by the pressure beam 2 which is operated by a screw spindle 1. This spindle or screw shaft is provided with comparatively steep threads of about 16 degrees pitch angle and pitch of about 25 millimeters (about one inch) as an instance. The spindle is rigidly secured to the pressure beam 2. This spindle or shaft is movable in a nut 3 which is rotatably journaled by means of ball bearings 5 in the casing 4. The screw nut 3 is provided with a collar adapted to absorb the compressing pressures which are transmitted to the casing 4 by means of the ball bearing 5. The casing 4 is secured to the frame 10 of the machine.

At the upper end of the screw nut 3 a hand wheel 6 is secured by means of which the screw nut 3 may be turned, so as to raise or lower the spindle 1. By the rotation of the wheel 6 in the direction of the arrow *x* the spindle is raised while on being rotated in the direction of the arrow *y* it is lowered. Any unintended automatic rotation of the screw nut 3 is prevented by frictional braking or locking means which in the exemplification shown comprises an arresting dog 7 and a hand lever 8.

To the boss 4a of the casing 4 is pivotally connected the hand lever 8 on the bolt 9. The pawl or dog 7 is also pivoted on the bolt 9 and has a stud 8a which cooperates with the abutments 8b and 8c.

The spring 11 connects the casing 4 and the hand lever 8 and tends to rotate the latter in the direction *x*. The hand lever 8 bears with its abutment 8b against the stud 8a in the pawl 7 and forces the latter into the key groove 6a within the hand wheel 6. In this position of the hand wheel 6, the hand wheel cannot be rotated in the direction *x* because the arresting dog or pawl 7 is jammed in the key groove 6a and is more firmly jammed therein owing to the inclined position opposite to the direction of rotation *x*. Since the hand wheel 6 and the nut 3 are secured to

gether, the latter is also prevented from rotation in the direction x . If the hand wheel 6 and the nut 3 respectively are rotated in the direction x , a light pressure against the hand lever 8 is sufficient so that the abutment 8c presses against the stud 8a and lifts the pawl or dog 7 out of the groove 6a.

The rotation of the hand wheel 6 in the direction y is always possible because the pawl 7 does not exert an arresting action but bears only with the light pressure through the spring 11 in the groove 6a of the hand wheel 6.

The mode of operation of the device is substantially as follows:

If the pressure beam 2 has to be lowered onto the pile from its raised position a slight movement of the hand of the operator will produce a sufficient rotation on the hand wheel to cause the pressure beam to become firmly seated on the pile which is thereby slightly compressed in consequence of the momentum of the force. For the full, complete compression however it will then require only a sudden, forcible, jerking movement with both hands and outstretched arms on the hand wheel, so that with two grasping steps the entire pressing operation is completed. Any return movement of the pressure beam is prevented by the arresting of the dog 7. If after the performing of the cut the pressure beam is to be raised, a slight turning of the hand lever 8 by hand will cause the arresting dog to be released which may even take place during the raising of the knife. As a result of the high compressing pressure which keeps the pressure beam seated upon the pile the hand wheel with the spindle nut is automatically rotated towards the left, so as to cause the raising of the shaft or the spindle 1. After the pressure beam has been sufficiently raised, the hand lever 8 is released and the movement of the pressure beam is stopped. Thus, the raising of the pressure beam is effected automatically without necessitating any special expenditure of force, so that the pile is already exposed, before the knife has reached its highest position, and thus by the device described the manipulation of the machine is facilitated and rendered more rapid.

It should be understood that the device described is susceptible of various modifications and changes in accordance with varying conditions of its application, and without thereby deviating from the scope and spirit of the invention, as defined in the appended claims.

I claim:

1. In a cutting machine for paper, cardboard and the like in combination, a pressure beam, a spindle, operatively connected to the beam and having comparatively steep, substantially non-locking threads, rotatably and non-slidably mounted means for supporting

and operating the spindle and arresting means, operatively associated with the supporting means and adapted to lock the same in its particular operative position.

2. In a cutting machine for paper, cardboard and the like in combination, pressing means, a spindle, operatively connected to said means and having substantially steep-pitched threads, a nut on said spindle and frictionally operating locking and arresting means operatively engageable with the nut.

3. In a cutting machine for paper, cardboard and the like in combination; a support, paper-pressing means thereon, a spindle operatively connected to said means having threads thereon, a screw nut on the support surrounding and supporting the spindle, rotating means for the nut and frictionally operating locking means on the support engageable with the rotating means and adapted to arrest the same against rotation in a certain direction and manually operated actuating means for the locking means.

In testimony whereof I affix my signature.

KARL STEGMANN.
